UNITED STATES PATENT OFFICE.

EUGENE CROWE, OF BROOKLYN, NEW YORK, ASSIGNOR TO THE E. S. HIGGINS CARPET COMPANY, OF NEW YORK, N. Y.

DESIGN FOR CARPET.

SPECIFICATION forming part of Design No. 25,495, dated May 12, 1896.

Application filed April 11, 1896. Serial No. 587,208. Term of patent 31 years.

To all whom it may concern:

Be it known that I, EUGENE CROWE, a citizen of the United States, residing at Brooklyn, in the county of Kings and State of New York, have invented and produced a new and original Design for a Carpet, of which the following is a specification, reference being had to the accompanying drawing, forming a part thereof, which represents a face view of a carpet in which the new design is embodied.

The invention relates to a design to be worked into or upon surfaces, such as carpets and similar fabrics; and it consists in the novel conformation of the figures, as herein shown and claimed.

The body A and the border also, if one is used, are decorated with composite scrolls B, the component parts whereof are a panel-

scroll figure b^1 , a lower curved foliated figure b^1 , connected therewith, a second foliated figure b^2 , continuing the curve of the said lower figure, and a third foliated figure b^3 , which extends from the second corresponding figure b^2 and is curled in the space between the panel-scroll and the intermediate foliated figure. Fragments of various composite scrolls appear in the drawing, together with a complete composite scroll.

I claim—

The design for carpets, substantially as shown.

EUGENE CROWE.
